UNITED STATES PATENT OFFICE.

CHARLES B. THOMPSON, OF NORTH TONAWANDA, NEW YORK, ASSIGNEE TO THOMPSON
HEATER CORPORATION, OF BUFFALO, NEW YORK, A CORPORATION OF NEW YORK.

BOILER.

1,326,621.

Specification of Letters Patent. Patented Dec. 30, 1919.

Application filed December 11, 1916. Serial No. 136,183.

To all whom it may concern:

Be it known that I, CHARLES B. THOMPSON, a citizen of the United States of America, and a resident of the city of North Tonawanda, county of Niagara, and State of New York, have invented new and useful Improvements in Boilers, of which the following is a specification.

My invention relates generally to boilers and more particularly to boilers and furnaces used for domestic and house-heating purposes.

It is well known to those skilled in the art, that many attempts have been made to produce a smokeless boiler. These attempts apparently failed because designers worked on the theory that if air was admitted to the fuel at the proper time and place, it would prevent smoking. Smoke is formed by fine particles of carbon being carried with the gases in the process of distillation. These gases leave the burning zone in strata, and unless the various strata are intimately mixed, all the air that may be admitted to the gases will not prevent smoking. Jets of steam are sometimes blown in over the fire to prevent smoking and where the desired end is accomplished, the strata of the gases have been thoroughly broken up and intermixed before the gases leave the hottest part of the burning zone. Such mechanical appliances are, however, not available in domestic or house-heating boilers.

The principal object of my invention has been to provide a boiler which shall positively prevent smoking. This is accomplished by causing the gases to pass downwardly and by thoroughly breaking up their strata after coming from the fire, for it is well known, that the volatile gases which are distilled at the top of the fire are at a low heat and if they are permitted to pass out into the chimney without being heated to a high temperature and commingled, smoke will be the result.

Another object has been to provide a boiler which shall be adjustable so as to accommodate different kinds of coal. If a boiler is designed to use coarse coal and the user desires to burn the finer coals, unless some provision is made for adjusting the coal bed, the resistance of the fuel bed to

the passage of the air would be so great that the chimney would not be able to furnish the necessary draft. If, on the other hand, the furnace was designed for burning fine coal and it was desired to change to coarser coal, the fuel bed would be so thin that the passage of the air through the fire would be excessive and a large amount of heat would be lost up the chimney and only a comparatively small amount utilized in the furnace. My boiler provides means for adjusting the thickness of the coal bed.

Furthermore, my boiler is so designed that the furnace section is separate from the boiler section and, if it is desired to change the firing period of the boiler, it is only necessary to change the size of the furnace section thereof.

Moreover, the magazine of my boiler may be charged with coal without checking the continuous operation of the boiler.

The furnace and grate members of the furnace section of my boiler are so designed that a fire may be easily started at the inner ends of the grates, where the fuel bed is the thinnest, which greatly facilitates the convenient operation of the boiler. After the fire has been started, it will continue to burn until the front part of the boiler is reached and, as my boiler is designed to have air supplied to the fire in front of the grates, as well as through the grates the operation of the fire is not impaired when the grates become clogged with ashes.

A further object of my invention has been to provide water cooled grates for my boiler.

These objects and advantages have been accomplished by the device shown in the accompanying drawings. In the drawings:

Fig. 1 is a sectional side elevation of my complete boiler.

Fig. 2 is a sectional plan view taken on line 2-2 of Fig. 1.

Fig. 3 is a fragmentary front sectional view taken on line 3-3 of Fig. 1.

Fig. 4 is a fragmentary plan view of the grate bars of my device showing their attachment to the boiler sections and the front of the furnace part of the boiler.

Fig. 5 is a side elevation of one of the grate bars, showing its connection to the boiler section.

Fig. 6 is a sectional side elevation of one of the grate bars and is taken on line 6—6 of Fig. 4.

Fig. 7 is a sectional elevation of one of the grates, taken on line 7—7 of Fig. 5.

Fig. 8 is a similar view taken on line 8—8 of Fig. 5.

Fig. 9 is a similar view taken on line 9—9 of Fig. 5.

10 Referring now to the drawings and more particularly to Figs. 1 to 3 inclusive, 10 represents the boiler part of my device and 11 the furnace part thereof. These parts of my device are separate from each other 15 and are fastened together by any suitable means. This arrangement provides a boiler, which may have the size of its coal magazine easily changed. The boiler part of my device comprises a plurality of boiler sections 20 12. Each of these sections, except the end ones, is symmetrical in form. Each section is bounded by a rib 13 which extends entirely around the section, except where openings are provided, and thus forms the 25 usual flues for the gases between adjacent sections. In the front at the lower side portion of each of the boiler sections is provided a plurality of louvers 14, which provide spaces, opening into the furnace part 30 of my boiler. These louvers are arranged opposite the fire in the furnace part of my boiler and are inclined downwardly and outwardly, so that the heated gases may have free access to the flues of the boiler, and at 35 the same time prevent the coal in the furnace from dropping into the boiler sections.

Immediately above the louvers 14 of the boiler sections is provided a rearwardly and downwardly extending lower flue rib 15, 40 which has its upper end integral with the outer rib 13 at the front of the section and its lower end curved downwardly and forwardly, so that a whirlpool action of the gases will be caused as they come from the 45 fire. Some distance above the lower flue rib 15, is arranged an upper flue rib 16. This rib is inclined upwardly from the rear of the section and has its rear end integral with the rib 13 at the rear of each section 50 and its upwardly inclined front end extending to a point near the front rib 13 of the section. Arranged immediately above the inner end of the flue rib 16 is a flue outlet 17. This outlet is formed in a number of 55 boiler sections 12, and extending across the outlets is a flue outlet collar 18, to which is secured the chimney flue 19. 20 is a damper arranged in the flue outlet collar 18. It will thus be seen that a serpentine channel or 60 flue is provided through the boiler sections for the gases. An opening 21 is provided in each of the sections, immediately above the flue rib 16 and these openings form a means of communication between the sections, 65 whereby the burned gases may reach the

draft opening. An opening 22 is also provided in each of the sections, which communicate with suitable openings in the end sections (not shown), whereby the boiler flues may be easily cleaned. An opening 23 70 is also provided in the lower rear part of each of the sections and is closed by means of a collar 24 and a door 25. These openings provide additional means of access to the flues of the sections for cleaning purposes, and also provide means of access to the flues for the convenient installation of 75 gas burners.

The water spaces in adjacent boiler sections are connected together by means of the 80 usual tapered nipples (not shown), hubs 26 and 27 being provided at the upper and lower parts of each section, respectively, for this purpose, and also for inlet and outlet pipes (not shown) to and from the boiler. 85 The boiler sections of my device may be secured together by any well known means, but in my preferred way, I provide a central, outwardly-extending flange 28 at each corner of each section. Each of these flanges is provided with two apertures and when assembled a bolt 29 is passed through the upper holes of the flanges of the first and second sections and then another bolt is passed through the lower holes of the flanges 90 of the second and third sections, and so on throughout the remaining sections, so that the bolts 29 are arranged in staggered relation across the boiler part of the device. A stop lug 30 is provided on each side of 95 each of the flanges 28 and extends upwardly to a point slightly above the general finished surface of the boiler section. The distance between the finished face of the section and the upper face of this stop lug is just enough 100 to allow for the usual packing, which is placed between the boiler sections.

An end boiler section 32 is secured at one end of the boiler part of my device and an end boiler section 33 is secured to the other 110 end thereof. Each of these sections is provided on its inner surface with ribs and louvers in the same way as each of the regular boiler sections, but the outer wall thereof is plain. In the front face of each of these 115 end boiler sections is provided an upper boss 34 (shown in dotted lines in Fig. 1) and a lower boss 35, respectively, each of which is provided with an interiorly screwthreaded aperture, which is in communication with 120 the water space of the boiler section, to be hereinafter referred to.

The furnace part 11 of my boiler comprises a front wall 36, in which is provided the usual fire door 37 and the ash pit door 38. End walls 39 and 40 are provided at 125 each end of the furnace part and a top 41, having a magazine charge door 42 in its face, covers the furnace part.

Each of the furnace ends 39 and 40 is 130

provided with an inner wall 43 and an outer wall 44, thus forming in each a water space 45. An upper wall 46 closes the water front at the top and a lower wall 47 closes the same at the bottom. An end wall 48 is provided at the front of the water space. An end wall 49 is also provided at the rear of the water space and is arranged adjacent to the front of the end boiler sections 32 and 33. Each of the furnace ends extend preferably only to the grates of the furnace and an ash pit plate 50 is arranged beneath each of the furnace ends extending therefrom to the floor line of the boiler. In each of these plates is arranged an air opening 51 for the furnace, a damper 52 being provided in each opening.

Arranged near the front of the furnace part of my boiler is a water front 53. This water front is provided at each side of its upper end with a water outlet pipe 54. These outlet pipes are arranged to pass through suitable apertures in the inner wall 43 of each of the furnace end walls 39 and 40, whereby a pivotal support for the water front is provided. Connecting each of the outlet pipes 54 with the threaded aperture in the boss 34 of the end boiler section, is a pipe 55 (shown in dotted lines of Fig. 1). Each of these pipes 55 is arranged across the top of the water space 45 in the furnace end walls 39 and 40 and a branch pipe 56 connects this water space with each of these pipes, so that not only the water from the water front 53 but also the water from the water spaces of the furnace end walls 39 and 40 will be connected with the water space of the boiler part. The lower corner of the water front is cut away at each side thereof, thus forming recesses 57. The water inlet pipe 58 for the water front is secured into the vertical face of each of these recesses. 59 are the supply pipes, each of which has one end connected with the screwthreaded aperture in the boss 35 of each of the end boiler sections and the other end of each is connected, by means of the oblique pipe 60 and the horizontal pipe 61, to the inlet water pipe 58. By this arrangement it is possible, by increasing or decreasing the length of the pipes 60 and 61, to alter the position of the water front 53, so that either coarse or fine coal can be burned in the furnace. The pipes 59 lie directly beneath the lower walls 47 of the water spaces of the furnace end walls and a branch pipe 62 connects each of these pipes with the water space of each end wall. It will be seen that the water coming from the end boiler sections 32 and 33 will pass through the pipes 59 and supply the end furnace walls through the branch pipes 62, and the water front through the pipes 60, 61 and 58. The water from the water front and also that from each fur-

nace end wall will be conducted through the pipes 55 back to the end boiler sections.

Referring now particularly to Figs. 4 to 9, where I show the grate members of my boiler, it will be seen that a plurality of 70 separate grate members 63 are provided. Each of these grate members is substantially U-shaped in cross section throughout the greater part of its length and is provided with outwardly extending fingers 64 at each 75 side thereof (Figs. 7 and 8). At the inner end of each grate member is provided an annular projection 65 which is supported within an annular recess 66, formed by the flange 72 provided on the face of each of the boiler 80 sections 12. The outer end of each of the grate members is provided with an annular head 67, having its axis coincident with the annular projection 65. This head is supported by a semicircular flange 68, formed 85 integral with the furnace front 36. The head of each grate member is provided with a square-shaped aperture 69 (Fig. 9), which is in line with a circularly shaped aperture 70 formed through the face of the 90 furnace front 36, whereby a shaker handle, shown in dotted lines in Fig. 6, may be passed through the aperture 70 and engaged with the aperture 68 for separately rocking each grate. A water pipe 71 is screwthreaded 95 into the front of each of the water sections and is arranged concentric with the annular recess 66. One of these pipes is provided for each grate member and is arranged to be encircled thereby, as clearly 100 shown in Figs. 6 and 7. Each of the pipes 71 is in communication with the water space of the boiler section to which it is attached and is closed at its outer end, so that the 105 grate members are kept cool and at the same time the heat therefrom is utilized by being taken up by the water from the boiler section.

From the drawings, and more particularly from Fig. 1, it will be seen by the arrows that air is taken into the furnace through the air opening 51 provided at each side thereof. This air will not only pass up between the fingers of the grate members, which are directly beneath the fire, 110 but also between those which are in front of the fire. Thus, the fire will receive air from the front and from beneath. By this provision, if the grates should be clogged with ashes, the fire would not be impaired 115 but would receive its proper amount of draft. Furthermore, it will be seen from Fig. 1, that the fire bed is very thin at the extreme inner ends of the grate members, whereby the kindling of a fire in the furnace 120 is greatly facilitated. The gases coming from the furnace will pass into the flues of the boiler sections between the louvers 14. Just as soon as the gases enter the flues of the boiler sections they will be projected 125 130

against the lower flue ribs 15 and deflected downwardly so that they will strike the curved end of these ribs and be projected inwardly in a circular direction and at a 5 point just opposite the hottest part of the fire and where the gases coming therefrom are the highest in temperature. The whirling action thus produced will thoroughly and effectively break up all strata of the 10 burned gases and thus thoroughly commingle them with the incoming oxygen, thereby causing all the combustible gases to burn to CO₂. No gases can escape into the flues without first passing through the most intense 15 heat of the combustion chamber. After the gases leave this point, they are passed upwardly and projected inwardly by the upper flue ribs 16. At the outer ends of these ribs they are drawn forwardly by the draft 20 and pass into the chimney stack 19.

Obviously, some modifications of the details herein shown and described may be made without departing from the spirit of my invention or the scope of the appended 25 claims, and I do not, therefore, wish to be limited to the exact embodiment herein shown and described.

Having thus described my invention, what I claim is:—

30 1. A boiler comprising a boiler part and a furnace part, means for separably uniting the parts, the furnace part comprising a grate and a fuel magazine, the boiler part being provided in its lower portion with flue openings leading into the combustion zone of the furnace part, and comprising flues and a plurality of louvers arranged in the openings between the said parts.

2. A boiler comprising a boiler part and 40 a furnace part, means for separably uniting the parts, the furnace part comprising a grate and a fuel magazine, the boiler part being provided in its lower portion with flue openings leading into the combustion zone of the furnace part, and comprising flues and means, located in the openings between the said parts, for preventing the fuel from passing from the furnace part to the boiler part.

50 3. A boiler comprising a boiler part and a furnace part, means for separably uniting the parts, the furnace part comprising a grate and a fuel magazine, the boiler part being provided in its lower portion with flue 55 openings leading into the combustion zone of the furnace part, and comprising flues and a plurality of louvers arranged in the openings between said parts and inclined upwardly and inwardly toward the boiler part.

60 4. A boiler comprising a boiler part and a furnace part, means for separably uniting the parts, the furnace part comprising a plurality of individually movable grate members and a fuel magazine, the boiler

part being provided in its lower portion with flue openings leading into the combustion zone of the furnace part, and comprising flues and a plurality of louvers arranged in the openings between the said parts. 70

5. A boiler comprising a boiler part and a furnace part, means for separably uniting the parts, the furnace part comprising a plurality of water cooled movable grate members and a fuel magazine, the boiler 75 part being provided in its lower portion with flue openings leading into the combustion zone of the furnace part, and comprising flues and a plurality of louvers arranged in the openings between the said parts. 80

6. A boiler comprising a boiler part and a furnace part, means for separably uniting the parts, the furnace part comprising a casing, a grate member, a fuel magazine comprising an adjustably mounted water jacketed front, and means for supplying water from the boiler part to the water jacketed front, the boiler part being provided in its lower portion with flue openings leading into the combustion zone of the furnace 90 part, and comprising flues and a plurality of louvers arranged in the openings between the said parts. 85

7. A boiler comprising a boiler part and a furnace part, means for separably uniting 95 the parts, the furnace part comprising a casing, having water jacketed ends, a grate member, a fuel magazine, and means for supplying water from the boiler part to the furnace ends, the boiler part being provided in its lower portion with flue openings leading into the combustion zone of the furnace 100 part, and comprising flues and a plurality of louvers arranged in the openings between the said parts. 105

8. A boiler comprising a boiler part and a furnace part, means for separably uniting the parts, the furnace part comprising a casing, a grate member, the casing being provided with end walls, each having an adjustable opening therein, disposed below the grate member, a fuel magazine, the boiler part being provided in its lower portion with flue openings leading into the combustion zone of the furnace part, and comprising flues and a plurality of louvers arranged in the openings between the said parts. 110 115

9. A boiler comprising a boiler part and a furnace part, means for separably uniting the parts, the furnace part comprising a casing, having water jacketed ends, a grate member, the casing being provided with end walls, each having an adjustable opening therein, disposed below the grate member, a fuel magazine, the boiler part being provided in its lower portion with flue openings leading into the combustion zone of the furnace part, and comprising flues and a plurality of louvers arranged in the openings between the said parts. 120 125 130

10. A boiler comprising a boiler part and a furnace part, means for separately uniting the parts, the furnace part comprising a grate and a fuel magazine, the boiler part, 5 being provided in its lower portion with flue openings leading into the combustion zone of the furnace part, and comprising flues, a plurality of louvers arranged in the openings between the said parts, and down- 10 wardly, inwardly and forwardly extending lower ribs integral with the boiler part and connected to the front wall thereof, ar- ranged opposite the louvers and having their upper ends extending above the louvers 15 and their lower ends extending downwardly beyond them.

11. A boiler comprising a boiler part and a furnace part, means for separably uniting the parts, the furnace part comprising a 20 grate and a fuel magazine, the boiler part being provided in its lower portion with flue openings leading into the combustion zone of the furnace part, and comprising flues, a plurality of louvers arranged in the open- 25 ings between the said parts, serpentine flues extending from the louvers, having the entrance portions at the louvers and then ex- tending downwardly, then upwardly, then forwardly, and then outwardly.

30 12. A boiler comprising a boiler part and a furnace part, means for separably uniting the parts, the furnace part comprising a grate and a fuel magazine, the boiler part, being provided in its lower portion with 35 flue openings leading into the combustion zone of the furnace part, and comprising flues, a plurality of louvers arranged in the openings between the said parts, down- 40 wardly, inwardly and forwardly extending lower ribs integral with the boiler part and connected to the front wall thereof, ar- ranged opposite the louvers and having their upper ends extending above the louvers and their lower ends extending downwardly 45 beyond them, a flue outlet, and upper flue 45 ribs integral with the boiler part having their rear ends connected to the rear of the boiler, the upper flue ribs being upwardly and forwardly inclined and positioned below 50 the flue outlet.

13. A boiler comprising a boiler part and a furnace part, means for separably uniting the parts, the furnace part comprising a grate and a fuel magazine, the boiler part 55 comprising boiler sections, flues formed in the boiler sections, the boiler sections being each provided with flanges, each formed with two apertures, and fastening means passing through the apertures of adjacent 60 boiler sections and arranged in staggered relation.

14. A boiler comprising a boiler part and a furnace part, means for separably uniting the parts, the boiler part comprising boiler sections, each of the sections being provided 65 with flues and with flue openings in its lower portion leading into the combustion zone of the furnace part, and louvers arranged in the openings, the furnace part comprising a plurality of movable grate members, each 70 member comprising a U-shaped rocking grate bar provided with fingers, and an outwardly extending water pipe connected with each of the boiler sections, one of the 75 grate bars being disposed over each of the pipes and rotatably supported by the boiler part and the furnace part.

15. A boiler comprising a boiler part and a furnace part, means for separably uniting the parts, the boiler part comprising boiler 80 sections, each of the sections being provided with flues and with flue openings in its lower portion leading into the combustion zone of the furnace part, and louvers ar- ranged in the openings, the furnace part 85 comprising a plurality of movable grate members, each member comprising a U- shaped rocking grate bar provided with fingers, an outwardly extending water pipe connected with each of the boiler sections, 90 one of the grate bars being disposed over each of the pipes and rotatably supported by the boiler part and the furnace part, and means for individually rocking the grate members.

16. A boiler having a furnace part comprising a casing, an adjustable water front movably mounted within the casing, a fuel magazine bounded on one side by the water front, a grate member, and adjustable means 100 connecting the water front with the water space of the boiler.

17. A boiler comprising a boiler part and a furnace part, means for separably uniting the parts, an adjustable water front mov- 105 ably mounted within the casing, a fuel mag- azine bounded on one side by the water front, a grate member, and adjustable means connecting the water front with the water space of the boiler.

18. A boiler comprising a boiler part and a furnace part, the furnace part comprising a casing having water jacketed ends, a grate member, an adjustable water front movably mounted within the casing, a fuel 115 magazine bounded on one side by the water front, and means for supplying water from the boiler part to the furnace ends and the water front.

In testimony whereof I have hereunto 120 signed my name.

CHARLES B. THOMPSON.
